United States Patent

Des. 235,667
Patented July 1, 1975

235,667

RELIGIOUS PLAQUE

Winnie C. Whitmire, P.O. Box 203,
Deming, N. Mex. 88030

Filed Jan. 24, 1972, Ser. No. 220,547

Term of patent 14 years

Int. Cl. D11—02

U.S. Cl. D29—23 A

Fig. 2

FIG. 1 is a perspective view of a religious plaque showing my new design;

FIG. 2 is a top view thereof; and

FIG. 3 is a rear plan view reduced in size.

I claim:

The ornamental design for a religious plaque, as shown.
